UNITED STATES PATENT OFFICE.

ERNEST L. GALE, SR., OF YONKERS, NEW YORK, ASSIGNOR TO OTIS ELEVATOR COMPANY, OF JERSEY CITY, NEW JERSEY, A CORPORATION OF NEW JERSEY.

BRAKE-MAGNET-DEMAGNETIZING DEVICE.

1,152,501.

Specification of Letters Patent.

Patented Sept. 7, 1915.

Application filed July 14, 1910. Serial No. 571,899.

To all whom it may concern:

Be it known that I, ERNEST L. GALE, Sr., a citizen of the United States, residing at Yonkers, in the county of Westchester and State of New York, have invented a new and useful Improvement in Brake-Magnet-Demagnetizing Devices, of which the following is a specification.

My invention relates to a demagnetizing device. It is more particularly designated and described as a brake demagnetizing device for an alternating current brake and is shown in connection with elevator apparatus.

One of the objects of the invention is to provide means for demagnetizing a magnet after the energizing circuit is cut off.

A further object is automatically to open the demagnetizing circuit when the magnet has been demagnetized.

In the accompanying drawing a motor M and a traction drum D are shown, operative in the ordinary way to raise and lower the car C and the counterweight W. The supplying of current to the motor is effected by means of the reversing switches R and R' which are controlled by the switch K in the elevator car C.

The brake B is preferably of the type shown, in which the magnet windings 9 are connected in parallel with the motor M and the brake pulley 3 is located on the motor shaft 2. The cores 6 are secured to the brake levers 4, and the brake shoes 5 are adapted to bear upon the brake pulley 3. Brake windings 9 are wound about the magnet core 10, and when energizing current flows in the brake windings the cores 6 are drawn inwardly. A rod 7 passes

through the upper extremities of the brake levers 4, and the springs 8 mounted thereon are operative to apply the brake shoes 5 to the brake pulley. When, however, the magnet cores 6 are drawn inwardly the pressure of the springs 8 is overcome, the upper extremities of the brake levers 4 are moved apart and the brake pulley 3 is free of the brake shoes 5. This movement apart of the brake levers is relied upon to operate

certain circuit closing devices; at the extremity of each brake lever 4 are pivotally mounted a bell crank lever 12 and a rod 11, each rod being attached to the opposite bell crank lever. These levers 12 are operative

to join the contacts 13 and 14 when the

brake levers 4 are moved apart. This action closes circuits from the mains through the resistances 15 and 15' to the points 16 and 16' respectively, and in the ordinary energization and operation of the brake has no appreciable effect, since the resistances 15 and 15' are high enough to restrict the flow of too much current. If the contacts 13 and 14 are joined while the reversing switch R is closed, the resistances 15 and 15' are each connected across the mains, but if the reversing switch R' is closed when the contacts 13 and 14 are joined, the resistances are short-circuited and receive practically no current. The usefulness and effect of my invention become apparent when there is sufficient residual magnetism in the magnet, or when the cores 6 are sufficiently attracted to hold them in their energized position even after the energizing current for the motor and brake has been cut off. In such an event it is evident that if the elevator car C is heavily loaded, it will tend to fall since there is no brake to restrain such tendency. But if the cores 6 are so attracted and held, the contacts 13, 14 are joined by the operation of the bell crank levers 12, and demagnetizing circuits are closed through the brake windings 9. These circuits may be traced from the supply mains through the resistances 15, 15' to the points 16, 16'; thence through the brake windings 9 and by way of conductor 17 to the common wire main. Thus it is seen that whenever the magnet cores are magnetically held after the energizing current has been cut off, a circuit is made effective to demagnetize the brake magnet and magnet cores of residual magnetism.

The theory of operation involved in the demagnetization of the brake magnet is briefly as follows: As the brake magnet is excited by an alternating current, the magnetism fluctuates rapidly, passing periodically from zero to a maximum and then through zero and to a maximum in the reverse direction and back to zero, etc. That is, the magnetism responds to the exciting current, and when the circuit for the latter is opened the magnetic flux and consequently the residual magnetism will depend on the phase of the exciting current at the instant the circuit is broken. When therefore the reversing switch R or R' is opened the residual magnetism in the brake

magnet may or may not be sufficient to hold the brakes off and the switches 13 and 14 closed. Assuming the residual magnetism is sufficient to hold these switches 13 and 14 closed, current flows in the demagnetizing circuits as soon as the reversing switch is opened. This current, owing to the high resistances 15, 15', in the circuits, is weak and its magnetizing power insufficient to hold the brake off, but when opposed to the residual magnetism is ample to reduce the latter and release the brake.

A further feature of my invention consists in the opening of this demagnetizing circuit after the brake has been demagnetized. This is effected by the springs 8 which press the brake levers together, thereby moving the bell crank levers 12 to separate the contacts 13 and 14.

It is evident that my invention is effective automatically to close a demagnetizing circuit, or circuits, through the brake windings, and to open the said circuit when its object has been attained. The special adaptation and application to elevator service has been pointed out. It is to be understood however, that I wish not to be specifically limited to the embodiment herein disclosed; for it is evident that those skilled in the arts to which the invention appertains may make various changes without departing from the spirit or scope of the invention.

What I claim and desire to secure by Letters Patent of the United States is:

1. The combination of an electromagnet and its armature, an energizing circuit therefor, a switch to open and close the said circuit, and automatic means controlled by said electromagnet to supply a deenergizing current only when said switch is opened and thereby reduce the residual magnetism and release the magnet armature.
2. The combination of an electromagnet and its armature, an energizing circuit therefor, a switch to open and close the said circuit, and a demagnetizing circuit controlled by the said switch and electromagnet to effect the release of the armature.
3. The combination of an alternating current electromagnet and its armature, circuit connections therefor, a switch to open and close the circuit, and automatic means controlled by the electromagnet and rendered active by the opening of said switch to demagnetize the electromagnet and release its armature.
4. The combination of an alternating current electromagnet and its armature, circuit connections therefor, a switch to open and close the circuit, and means controlled by said switch and by the armature to effect the demagnetization and release of the said armature should it fail to release upon the opening of the switch.

5. The combination of an electromagnet and its armature, an energizing circuit therefor, a switch to open and close the said circuit, and means controlled by said armature and rendered active upon the opening of said switch to effect the release of the armature upon its failure to release when the said switch is opened.

6. The combination with a magnet having a movable core, of an energizing circuit for the magnet, means for opening and closing said circuit, and means for automatically rendering effective an alternating current circuit through the magnet to demagnetize the magnet only when the residual magnetism retains the core in its energized position after the energizing circuit is opened.

7. The combination with a magnet having movable cores, of an energizing circuit for the magnet, means for opening and closing said circuit, a demagnetizing circuit for said magnet, contacts for maintaining said demagnetizing circuit through the magnet winding when residual magnetism retains the cores in an energized position after the energizing circuit is opened and means for automatically opening said contacts to interrupt the demagnetizing circuit after the demagnetization of the magnet of residual magnetism.

8. The combination of an alternating current magnet having a movable core; a normally open demagnetizing circuit for the magnet winding, and means dependent upon the position of the core to effect the closure of said circuit.

9. The combination of an alternating current brake magnet, supplying mains therefor, resistance with one terminal connected to the mains, energizing circuits, a switch for opening and closing said energizing circuits, and circuit closing devices operated by the magnet when energized to short-circuit the resistance and to make the resistance effective only when the magnet cores are attracted after the energizing circuits have been opened.

10. The combination of an alternating current brake magnet with movable cores, current supply mains therefor, circuits from the mains to the magnet, a switch for opening and closing said circuits, resistance with one terminal connected to the mains, and means controlled by the magnet to short-circuit the resistance through the switch when the magnet is energized and to render the resistance effective in demagnetizing the magnet only when the magnet cores are attracted after the said switch has been opened.

11. The combination with an alternating current electromagnet having a movable core, an operating circuit therefor, of means controlled by the said magnet for maintaining a neutralizing influence upon said core to prevent residual magnetization thereof.

while the magnet is in operated position with its operating circuit opened.

12. The combination with an alternating current electromagnet having a movable core, an operating circuit therefor, of means controlled by the winding of said magnet for maintaining a neutralizing influence upon said core to prevent residual magnetization thereof while the magnet is in operated position and its operating circuit opened.

13. The combination with an alternating current electromagnet having relatively movable members and an energizing winding for bringing said members together, an operating circuit for the winding, of automatic means controlled by the magnet for reducing the current through said winding and preventing said members from sticking together when the operating circuit of the magnet is not effective.

14. The combination with an alternating current electromagnet having normally separated magnet cores, an operating circuit for said magnet for effecting a relative movement of said cores toward each other, and means controlled by said magnet cores for passing a small current through the winding of said magnet to overcome the residual magnetization of said cores when the current in the operating circuit is reduced.

15. The combination with an alternating current electromagnet having normally separated members and an energizing winding for bringing said members together, an operating circuit for said winding, of a demagnetizing circuit controlled by the magnet and containing a predetermined amount of resistance to limit the current through the winding and eliminate the tendency of the members to stick together after the operating circuit is opened.

16. The combination with an alternating current electromagnet having normally separated members, a switch for closing a circuit through the winding of the electromagnet to bring the members together, and means controlled by the said switch, and dependent upon the position of the said members for closing a circuit containing resistance or reactance for the purpose of demagnetizing the said members.

17. The combination with an alternating current electromagnet having normally separated members, a switch for closing a circuit through the winding of the electromagnet to bring the members together, and means controlled by the said switch and dependent upon the position of the said mem-

bers for establishing a neutralizing influence upon the members to overcome the residual magnetism of the said members.

18. The combination with an alternating current magnet having normally separated core members, means for closing a circuit through the winding of the magnet to move the core members together, and means controlled by said members and circuit closing means for reducing the current in said magnet winding to overcome the residual magnetization of the said core members.

19. The combination with an alternating current magnet having normally separated core members, means for closing a circuit through the winding of the magnet to move the core members together, and means controlled by said members and circuit closing means for permitting a small demagnetizing current in said magnet winding to overcome the residual magnetization of the said core members.

20. The combination with an alternating current magnet having normally separated core members, means for closing a circuit through the winding of the magnet to move the core members together, and means controlled by said members for establishing a circuit containing a predetermined amount of resistance therein in said magnet winding to eliminate the tendency of the said core members to stick together.

21. The combination with an alternating current magnet having normally separated core members, means for closing a circuit through the winding of the magnet to move the core members together, and means controlled by the core members for closing a circuit containing resistance or reactance through the said magnet winding to prevent residual magnetization of the core members when the circuit closing means is in open position.

22. The combination with an alternating current electromagnet, a magnetizing circuit therefor, and an additional circuit controlled by the said magnet for demagnetizing the latter upon the interruption of the magnetizing circuit.

23. The combination with an alternating current electromagnet, of a demagnetizing circuit therefor, and means controlled by the magnet for opening and closing said circuit.

In testimony whereof, I have signed my name to this specification in the presence of two subscribing witnesses.
